UNITED STATES PATENT OFFICE.

GLENN E. MORNINGSTAR AND JAMES G. MORNINGSTAR, OF GREENVILLE, OHIO.

ARTIFICIAL TEETH.

1,095,018.

Specification of Letters Patent. Patented Apr. 28, 1914.

Application filed May 12, 1913. Serial No. 767,240.

To all whom it may concern:

Be it known that we, GLENN E. MORNINGSTAR and JAMES G. MORNINGSTAR, citizens of the United States, residing at Greenville, in the county of Darke and State of Ohio, have invented certain new and useful Improvements in Artificial Teeth, of which the following is a specification.

This invention relates to artificial teeth, and its object is to provide improved means for securing porcelain facings to bridge work, whereby a facing may be renewed without removing the bridge from the mouth.

The construction of our improvement will be fully described hereinafter in connection with the accompanying drawing which forms a part of this specification, and its novel features will be set forth and defined in the appended claim.

In the drawings:—Figure 1 is a vertical section of a porcelain facing and its post, and a bridge to which our invention is applicable, Fig. 2 is a side elevation of our improved securing device, Fig. 3 is a side elevation illustrating the facing secured to a bridge, and Fig. 4 is a sectional view of the bridge.

The numeral 1 designates a porcelain facing in which is formed on its inner side a

vertical slot 2 adapted to receive a securing post 3 from the upper end of which projects a threaded pin 4 upon which is mounted a nut 5.

The numeral 6 designates a backing to 35 which the facing 1 is secured by means of the threaded pin 4, and nut 5.

In case of breakage of the facing 1 a new facing may be readily applied without removing the bridge, as will be apparent to 40 those skilled in the dental art.

Having thus fully described our invention what we claim and desire to secure by Letters Patent is:—

In dental bridge work, the combination 45 with a perforated backing and a removable facing, of a post adapted to fit within a slot formed in the facing, a threaded pin projecting at approximately a right angle from said post, an extension of the post projecting 50 beyond the pin to take into an undercut in the removable facing, and a nut mounted upon the inner end of said pin.

In testimony whereof we affix our signatures in presence of two witnesses.

GLENN E. MORNINGSTAR.

JAMES G. MORNINGSTAR.
